UNITED STATES PATENT OFFICE

AUGUST F. WILLIAMS, OF SOUTH EUCLID, OHIO, ASSIGNOR TO THE AMERICAN MULTIGRAPH COMPANY, OF CLEVELAND, OHIO, A CORPORATION OF OHIO

PRINTING MACHINERY

Application filed December 30, 1927. Serial No. 243,527.

This invention relates to a rotary printing machine, and particularly such machine equipped for printing addresses on envelopes, cards, etc. The machine is preferably of that type of addressing multigraph illustrated in Patents Nos. 1,625,256 and 1,627,240, issued to my assignee, The American Multigraph Company.

In the operation of machines made in accordance with the patents mentioned, it has been found that sometimes the imprint on the envelope is imperfect, a certain smudging taking place. Experimenting with various means to cure this defect, I have discovered that the desirable result can be accomplished by interposing a movable shield between the address-carrying drum and the envelope platen, this shield having sufficient opening for the imprint and moving with the envelope during the impression. While thorough tests have demonstrated that my movable shield prevents the smudging, the reason why this result takes place has not yet been clearly proven. Accordingly, I will fully describe the structure, as embodied by me, and then give my theory as to the reason for the operation.

In the drawings, Fig. 1 is a vertical transverse section through an addressing multigraph equipped with my invention; Fig. 2 is an enlarged substantially horizontal section through the envelope platen and adjacent parts, as indicated by the line 2—2 on Fig. 1; Fig. 3 is a vertical transverse section of the machine on the plane indicated by the line 3—3 on Fig. 2 looking in the opposite direction from Fig. 1; Fig. 4 is an enlargement of a portion of Fig. 2, with the drum in printing position; Figs. 5 and 6 are enlargements of the printing platen and shield shown in Fig. 1, in positions indicating the beginning of the envelope feed and near the conclusion of the impressing action, respectively; Fig. 7 is a perspective of the envelope shield alone; Fig. 8 is an elevation of the envelope pocket and the shield and carrier as mounted in the machine, looking toward the platen; Fig. 9 is a view of the movable envelope shield and its carrier; Figs. 10 and 11 are cross sections on correspondingly numbered lines on Fig. 9.

I will first briefly describe the addressing multigraph as illustrated in Figs. 1, 2 and 3. For a fuller description reference should be had to the prior patents mentioned.

As shown in the drawings, the printing machine proper comprises a rotary drum 10, mounted on a shaft 11, journalled in end frame plates 12 and 13 above a roller platen 14 mounted on a shaft 15. Gearing 16 and 17 and a suitable coupling connect the drum and platen. Any suitable means is provided for rotating the drum and platen.

Mounted on the drum may be means for printing the body of a form letter, as a blanket 20 (indicated conventionally in Fig. 1) stretched about a segmental portion of the drum. The segment is shown as a semi-cylinder resting on the end members 28 and 29 of the drum and held in place by a spring hook 24 engaging the shaft 11. An inking ribbon 25 has its ends wound on spools 27 carried between the end members of the drum, such ribbon extending intermediately about the type form. It will be seen that in the construction described, when the drum is rotated, paper fed between the drum and platen may be printed by the characters through the ribbon.

The body of the drum adjacent one edge of the segment 10 is shown in Fig. 1 as provided with pair of longitudinal channels 30, 31 for the reception of the removable address plate. This plate may be of the form shown conventionally at 32, having an arcuate intermediate region and depressed edge portions curled on themselves for strength, and adapted to occupy the channels 30 and 31 when it is shoved endwise into place. Between these channels is a portion of the drum providing a support for the intermediate portion of the plate. The plate, which is shown conventionally may, if desired, have raised projections like the blanket and carry similar embossed printing strips.

The address plates may be inserted manually or in other manner as desired, a different plate for each rotation. The paper may be fed manually or automatically as desired. The drawing illustrates at 40 and 41 (Fig. 1), a pair of feed rolls connected by gearing 100

43 (Fig. 3) with the platen gear 16 and operating to progress the paper to the region between the drum and the platen. The drawing also shows an ejector roll 45 (Fig. 1) coating with a stripper spring 46, and connected with the drum by sprocket and spur gearing 47 (Fig. 3), but these parts are shown merely incidentally.

The mechanism described enables the simultaneous printing of the body and address of an addressed letter through an inking ribbon with comparative rapidity. Mechanism which will now be described is provided to enable the envelope to be printed from the same address plate while in its same position on the drum.

The envelope printing platen, designated 50 is a segment on a roller 53 adjacent the drum, at the rear thereof on a shaft 51 parallel therewith. This segment has such arcuate extent as will coat with the address portion only of the address plate and not engage the salutation, should there be one on the plate. This platen 50 is normally idle but is arranged at the proper time to revolve in co-operation with the address plate at the same peripheral speed. To this end, the platen roller 53 is made loose on a shaft 51, and driven by a gear 52 meshing with the gear 17 on the drum. This platen roller is connectible for rotation with the gear 52 by a single rotation clutch designated 60 as a whole.

The clutch is of the single-rotation type, and may be of the form shown in Fig. 2. That figure shows the gear 52 journaled on a stud 55 mounted in an extension of the end plate 13. One member of the clutch consists of a disk 60 rigid with this gear 52 and shown as pinned to a hub on the gear; another member consists of a disk 61 rigid with the platen; a third member comprises an intermediate disk 62 having radial ribs 63 occupying corresponding grooves in the disk 61 (after the manner of an Oldham coupling), and the final member comprises a locking pin 65 adapted to lock the members 60 and 62 together. This locking pin is slidably mounted in the member 60 and may engage a notch in the member 62. The clutch pin 65 is normally held withdrawn by a lever 80, which constitutes part of the detecting mechanism, which will now be described.

On the printing drum is a cam 81 (Fig. 3) which on each rotation of the drum acts on a roller 82 on the end of an arm 83 pivoted at 84 and having a depending portion 85 to which is anchored a tension spring 86. This arm has an overhanging lip 87 which bears against a small compression spring, the other end of which bears against the arm 80, also pivoted at 84. The action of the cam accordingly is to raise the roller and swing the arm 80 toward the drum if the arm is free to move,

otherwise to compress the spring between the arm and the lip 87.

The arm 80 is normally held in the position shown in Fig. 3 by a latch arm 90 which is a rock arm on a shaft 91 which carries another rock arm 92 (Fig. 1) constituting a detecting finger. Extending between the drum and envelope platen is a suitable pocket, hereinafter described, for the envelope to be printed. The detector finger, when no envelope is present, extends through openings in the pocket as shown in Fig. 1, being held in that position by a light spring (not shown) acting on the rock shaft 91. The finger in such position holds the latch arm 90 in the position shown in Fig. 3 to prevent the action of the arm 80. Whenever an envelope is placed in the pocket, it swings the detecting finger 92 downwardly and thus rocks the latch arm 90 free from the arm 80. Under these circumstances when the cam 81 acts on the roller 82, the arm 80 is moved toward the drum. This withdraws the arm from the clutch pin 65 and the spring 66 forces the clutch pin into action, thus locking the platen shaft 51 to the driving pinion 52 and giving the platen 50 one complete revolution to print the address on the envelope.

Before the printing of the envelope is completed, the cam 81 will have cleared the roller 72 and the arm 80 will have returned to the position of Fig. 3 where its beveled edge 81 (Fig. 2) will engage the collar 67 on the clutch pin, and thus the clutch withdraws itself from action as the rotation is completed, stopping the driving of the platen 50.

I will describe my attachment, which is related to the envelope pocket between the drum and platen 50, as above mentioned.

As shown, particularly in Figs. 1, 5, 6 and 8, the envelope pocket in this case comprises a front plate 100 mounted on a cross rod 101; a bottom bar 102, and a rear plate 103 secured to this bottom bar and having ears 104 embracing a cross rod 105 and above that curving over the top of the platen, as shown at 106, and finally anchored to a cross bar 107. Both the front and rear plates 100, 103, are cut out for a distance greater than the length of the segmental platen, leaving openings for the platen to coat with the printing form. The opening in the front plate is shown at 109 in Fig. 8. In this open region is mounted a stationary upright plate 110 secured at its lower end to the cross bar 102. This plate 110 has an opening 112 through which the detector finger, above mentioned, loosely extends. The plate 110 has two upwardly projecting tongues 113, which leave a space between them somewhat greater than the length of the envelope platen.

The final member of the envelope holder comprises my movable shield, which is a plate 120 having an opening 121 slightly shorter

than the length of the platen, but longer than the longest address used on the machine. The width of this opening (that is, its vertical dimension) is greater than the arcuate distance across an address plate having the 5 largest number of lines employed. Accordingly, this opening is sufficient to allow the printing of any address within the range of the machine.

10 The shield 120 lies snugly against the plate 110 and is slidably held thereon by bent over end flanges 123 of the plate 120. In its lower-most position, the lower edge of the shield rests on the cross bar 102 of the envelope 15 pocket. A limit is provided for its upward movement by outwardly flaring edges 115 of the tongues 113 on the stationary plate 110. The movable shield is provided above the opening 121 with a ledge 127 extending in an 20 inclined direction toward the envelope, as shown in Fig. 6. At its lower end the shield has a horizontal flange 125, which is abutted by the lower edge of the inserted envelope.

25 In operation of the machine, the envelope (indicated at A in Figs. 5 and 6) is inserted into the envelope pocket between the front plate 100 and the rear plate 103. The lower edge of the envelope engages the bottom flange 125 of the shield and forces it down to 30 normal position if it be elevated. Now when the envelope platen is clutched in, and the rubber segment begins to coact with the envelope, the edge of this segment acts through 35 the envelope against the ledge 127 of the shield and starts lifting the shield, as the platen and drum rotate. This action is illustrated in Fig. 5. The ledge 127 apparently holds the envelope back against the platen so that it cannot bow through the opening 40 121 and inadvertently contact with the printing ribbon.

45 As the address carrying drum and the envelope platen continue to rotate in coaction, the envelope and shield are fed upwardly together, and the printing on the envelope is effected through the opening 121. This upward feed starts, as explained above, by the coaction of the edge of the platen with the shield ledge 127, but later is continued by the 50 pressure of the rubber segment against that portion of the shield which is opposite the ends of the opening 121. This shield is in effect gripped between the rubber segment on one side of the shield, and the inking ribbon overlying the printing form on the other side, which bears against the flanged over- 55 ends 123 of the shield.

60 At the start of the printing, the available portion of the opening 121 is narrow, by reason of the lower part of that opening being below the edge 116 of the plate 110, as shown in Fig. 9. This narrow opening will insure the envelope from inadvertently engaging the ribbon. As the printing is effected, and 65 the rubber platen on one side and the address

plate and ribbon on the other feed the envelope and shield upwardly, the available opening through the shield increases to allow the printing of the lower lines on the address, but I find it is not necessary to shut off the upper portion of the opening 121 as the ledge 70 127 holds the envelope back away from the printing drum sufficiently so there is no smudging.

75 As the rubber segment goes out of coaction with the address plate, after the address is printed on the envelope, continued rotation of the rubber segment continues to carry the envelope upwardly and then soft rubber pins 130 on the platten roller some distance back 80 of the segment, come into contact with the envelope and continue its upward feed until it is ejected over the shield portion 106. When these pins and the envelope have cleared the shield, there is only friction to 85 hold it elevated. It is very light and may remain elevated or drop by gravity. If it does not drop, the next inserted envelope, engaging the ledge 125, forces it down into normal position.

90 As heretofore mentioned, it has not been demonstrated just what causes the smudging in the machine as heretofore constructed, nor just why my movable shield cures the difficulty. I can, however, mention following characteristics which may throw light on the matter:

95 Without the shield the smudging does not always occur, but sometimes does, and it seems to be worse with addresses of short lines, than of long lines. Apparently, when my shield is not employed, there is sometimes a slipping of the address with reference to the envelope, as if the envelope did not travel quite as fast as the address plate, or did not start movement quite quickly enough. And sometimes it seems as if the envelope buckled in against the ribbon over a non-printing portion of the address plate.

100 My movable shield, by reason of surrounding the address region, may have the effect of preventing buckling of the envelope into undesirable contact with the ribbon. My movable shield having a ledge coacting with the upper edge of the rubber segment to grip the envelope between them, seems to lift the envelope instantly when the edge of the rubber segment comes into such coaction with the result that the envelope starts to move 105 instantly and there is no chance for a drag of the envelope with reference to the address plate. As the coactive rotation of the drum and platen continue, the shield is gripped between the rubber segment and the ribbon overlying the address plate, and thus continues to rise.

110 By reason of the flanged ends 123 on the shield, it can only rise strictly vertically, or at right angles to the line of printing contact, and hence, there is no opportunity for tipping the envelope, nor any 115 120 125 130

possibility of feeding one end faster than the other. Finally the shield presenting a movable member coacting with the ribbon, instead of a stationary member as heretofore, there is no drag on the ribbon tending to pull it over the type form.

Accordingly, my invention of the movable shield seems to accomplish the result of starting the envelope immediately, and feeding it truly, and preventing its buckling against the non-printing portion of the address plate, and preventing any drawing of the ribbon across the type form. Whether these characteristics, or any of them, are the correct explanation of the operation, prolonged tests have demonstrated that the movable shield described is effective to prevent the undesirable smudging.

I claim:

1. The combination with a rotary printing couple, of a movable shield standing between them having an opening through which the impression is effected, and a ledge projecting from the shield toward the platen and adapted to coact therewith.

2. The combination with a rotary printing couple including a segmental platen, of a thin movable shield standing between the members of the couple and having an opening through which the impression is effected, and means for guiding said shield, said shield having a ledge above the opening projecting toward the platen and adapted to coact with the edge of the platen to cause the raising of the shield.

3. The combination with a printing member and platen, of a slidably guided plate between them moved by the coaction of the couple, and having a shoulder adapted to be engaged by the edge of the material to be printed.

4. The combination with a rotary printing couple, a movable shield between them, having an opening through which the printing impression is made, means for guiding said shield during the impressing action, and a shoulder on the shield adapted to be engaged by the edge of the material to be printed, whereby the insertion of the material may return the shield.

5. The combination with a rotary printing couple, of an upright movable shield standing between them having an opening through which the impression is effected, and a ledge above the opening projecting from the shield toward the platen and adapted to coact therewith to cause the raising of the shield, said shield having a flange at its lower end on which the envelope is adapted to rest.

6. The combination of a rotary printing drum adapted to carry a removable address plate, a coacting segmental platen, an envelope pocket between the drum and platen having an opening for enabling coaction of the platen and address plate, said envelope

pocket carrying a movable shield which has an opening through which the impression is effected.

7. The combination of a rotary printing drum adapted to carry a removable address plate, a coacting segmental platen, an envelope pocket between the drum and platen having an opening for enabling coaction of the platen and address plate, said envelope pocket carrying a movable shield having an opening and provided with a ledge adapted to coact with the edge of the platen.

8. The combination of a rotary printing drum, a rotary platen member carrying a segmental platen, a stationary support extending between the drum and platen member, and a shield consisting of a thin plate slidably mounted on the stationary support and guided to move in a path at right angles to the line of printing contact, said plate having an opening through which the impression may be effected and portions at opposite ends of said opening adapted to be gripped by the drum and platen.

9. The combination of a rotary printing drum adapted to carry a removable address plate, a rotary platen member carrying a segmental platen, an envelope pocket between the drum and platen member, having a stationary plate, a shield consisting of a thin plate slidably mounted on the stationary plate mentioned, said shield and stationary plate having openings through which the impression is made.

10. The combination of a rotary printing drum adapted to carry a removable address plate, a rotary platen member carrying a segmental platen, an envelope pocket between the drum and platen member having an upright stationary plate, a shield consisting of a thin plate having turned over ends slidably embracing the stationary plate mentioned and having an opening juxtaposed with an opening in the stationary plate, said shield having a ledge above its opening with which the platen coacts to start the plate in movement, said plate also having a flange at its lower end which may be engaged by an envelope to return the shield to normal position.

11. The combination of a rotary printing drum having an inking ribbon, a segmental platen adapted to coact with the drum through the ribbon, and a movable shield between the drum and platen having a portion which is engaged by the ribbon.

12. The combination of a rotary printing couple, one member having an address plate covered by an inking ribbon and the other member having a segmental platen, and a movable shield between said members and means for guiding it substantially tangentially of the members during the impressing action.

13. The combination of a rotary printing drum having an inking ribbon, a rotary mem-

ber having a segmental platen adapted to coact with the drum through the ribbon, and a slidably guided shield between the drum and platen having a portion which is engaged by the ribbon, and having a ledge which bends the envelope against the edge of the platen.

14. The combination of a rotary printing drum having a removable address plate surrounded by an inking ribbon, a rotary platen member, a segmental platen thereon, mechanism for throwing the platen member into action at the proper time to coact with the address plate, an envelope pocket comprising two plate-like members extending between the drum and platen and having openings through which the printing is effected, a stationary guide carried by said pocket, and a slidably shield carried by the guide and having an opening through which the impression is made, said shield coacting on one side with the inking ribbon and on the other with the envelope and through the envelope with the platen.

15. The combination of a rotary printing member, a platen comprising a rotary carrier having a segmental platen portion, a movable shield lying between them having an opening through which the impression is made, and a lug on said carrier some distance from the segmental portion and adapted to engage the article printed to continue the feed thereof.

16. The combination of a rotary drum adapted to carry an address plate, a platen roller, having a segmental portion, a movable shield between the drum and platen, means for guiding said shield in a path substantially tangentially to the paths of the drum and platen, said shield having a portion adapted to be engaged by the platen whereby it may feed, and elastic lugs on the platen roller adapted to engage the article printed to continue the movement thereof.

17. In a printing machine, the combination with a rotary printing couple in which the platen is segmental, of an interposed shield mounted independently of the platen having an opening through which the printing impression is effected, and means independent of the couple for so guiding said shield that it may move with the material being printed during printing operation.

18. The combination with a rotary printing couple, a movable shield between the members of the couple and mounted independently of each of them and means whereby said shield is guided to move in a path substantially tangential to both members of the couple during the impressing action.

19. In a printing machine, the combination with the two members of a printing couple, of an interposed positioning device for the material to be printed, said device having an opening through which printing is effected,

and a movable shield extending crosswise of said opening.

20. In a printing machine, the combination with the two members of a printing couple, of an interposed pocket having two walls with openings through them through which printing is effected, and a movable shield within the pocket adapted to be moved by printing coaction.

21. In a printing machine, the combination with the two members of a printing couple, of an interposed positioning device for the paper, said device having an opening through which printing is effected, and a movable shield extending crosswise of the opening and having a ledge projecting toward the platen whereby the platen may lift the shield.

22. In a printing machine, the combination with the two members of a printing couple, of an interposed pocket having two walls with openings through them through which printing is effected, and a movable shield within the pocket having a ledge projecting toward the platen whereby the platen acting through the paper may lift the shield.

23. In a printing machine, the combination with a printing couple, of an interposed pocket into and out of which the material moves in opposite directions and which has an opening through which the printing impression is effected, and a shield over the opening adapted to be moved during printing operation.

24. The combination of a rotary printing member, a segmental form carried thereon, a segmental platen adapted to coact with the form, a pocket between the platen and form which may hold the paper in position, and a shield movable during printing independently of said positioning means.

25. In a printing machine, the combination of a printing drum and a segmental platen having rolling coaction, a pocket fixed between the two members of the couple and having two spaced walls with openings through which the platen acts, and a shield adapted to stand between the drum and platen and be moved by their coaction.

26. In a printing machine, the combination of a printing drum on a horizontal axis, a segmental platen on a horizontal axis behind the drum, and a substantially vertical pocket adapted to stand between the drum and platen and having an opening through which the platen acts, and a shield guided adjacent the pocket and arranged to be raised by their coaction.

27. The combination of an upwardly opening pocket into which an envelope may be dropped, a segmental platen adapted to act on the envelope through an opening in the pocket, means for turning the platen in such direction that it acts to feed the envelope upwardly, and a shield movably mounted and normally extending across said opening, said

shield being adapted to be acted on by the segmental platen and moved during the printing.

28. The combination with a rotary printing drum and a roller carrying a segmental platen behind it, a plate between them having an opening through which the segment of the platen may press the article to be printed against the drum, and a shield substantially parallel with and adjacent to said plate and extending across the opening, said shield being movably mounted independently of the drum and platen, whereby the segment may move the shield to idle position during the printing action.

29. The combination with a rotary printing drum and a roller carrying a segmental platen behind it and an envelope pocket between them having front and rear walls with openings through which the segment of the platen may press an envelope in the pocket against the drum, and a shield substantially parallel with the front wall of the pocket and lying directly behind such wall and extending across the opening, said shield being movable mounted independently of the drum and platen, whereby the segment may raise the blade approximately vertically during the printing action.

30. In testimony whereof, I hereunto affix my signature.

AUGUST F. WILLIAMS.
